UNITED STATES PATENT OFFICE.

ALFRED L. MADISON, OF NEW YORK, N. Y., ASSIGNOR TO WILLCOX AND GIBBS SEWING MACHINE COMPANY, OF NEW YORK, N. Y., A CORPORATION OF NEW YORK.

PRESSER-FOOT LIFTER FOR SEWING-MACHINES.

No. 818,896.

Specification of Letters Patent.

Patented April 24, 1906.

Application filed February 6, 1905. Serial No. 244,413.

To all whom it may concern:

Be it known that I, ALFRED L. MADISON, a citizen of the United States of America, residing in the borough of Brooklyn, city of New York, county of Kings, State of New York, have invented Improvements in Presser-Foot Lifters for Sewing-Machines, of which the following is a specification.

The object of my invention is to provide a simple, economically-manufactured, and efficient presser-foot lifter for sewing-machines.

In the accompanying drawings, Figure 1 is a rear view of a sewing-machine provided with my improvement. Fig. 2 is a transverse section, on a larger scale, on the line 2 2, Fig. 4. Fig. 3 is a transverse section on the line 3 3, Fig. 4. Fig. 4 is a sectional view on the line 4 4, Fig. 2; and Fig. 5 is an end view of the knee-lever.

In Fig. 1 I have indicated at A a sewing-machine head with a spring-pressed presser-bar B, carrying a presser-foot b of any usual construction. C is a bell-crank lever pivoted at c to the sewing-machine head and having one arm to bear against the under side of a stud b' on the presser-bar, while the other arm of this lever is joined by a suitable connecting-rod c' to the upper arm of a bell-crank lever D, pivoted at d to the sewing-machine head. The lower arm of this bell-crank lever D is connected, through a rod d', to a lever E, pivoted at e to a stud f on a bracket F on the under side of the work-table W. I prefer to employ a spring to tend to keep the outer end of this lever E, which is connected to d', pressed upward, so as to relieve the presser-bar spring of its weight. For this purpose I may cast on the stud f a cupped projection f' and on the back end of the lever E a corresponding cupped projection e', Figs. 2 and 3, and between these two projections and held in the cups thereof is placed a spiral spring s. On the other side of the pivoting-point of this lever I may provide

a stop e² on the lever to contact with a stop-lug f² on the stud f on the bracket to limit the extent of upward motion of the outer end of lever E, Fig. 2. To actuate this lever E to cause the presser-foot to be raised, I provide a cross-shaft G, which is mounted in the bracket F and in a second bracket F' on the under side of the work-table. This cross-shaft is provided with a cam g to bear on the

upper side of the lever E. This cam is constructed with flanges g' g', Figs. 2, 3, and 4, 55 to embrace the lever E sufficiently to always maintain the latter in position laterally. To the outer end of the shaft G, preferably beyond bracket F', is affixed a knee-lever H. I prefer the construction shown in Fig. 5. As 60 there shown, the hub of the lever is made with a wedge-shaped opening h of sufficient size to slip freely over the end of the shaft G, and opposite the wedged-shaped part of the opening I set through the hub of the lever at 65 right angles to the axis of the shaft a setscrew h', which when screwed up will bear against one side of the shaft and force the other side tightly into the wedged-shaped side of the opening. 70

As will be understood from the foregoing description and from the view Fig. 1, the sewing-machine operator has the knee-lever H in convenient position for his right knee, and when he wishes to raise the presser-bar 75 without using his hands for the purpose he simply moves his right knee to the right, pressing the lever H over in the direction of the arrow, Fig. 1, so that the cam g presses down the lever E, and through the rods d' c' 80 and bell-crank levers D C he raises the presser-bar B and its foot b against the presser of the springs. 85

I claim as my invention—

1. The combination of the presser-bar of a sewing-machine with a knee-lever and its cross-shaft, a cam on the cross-shaft, and a lever on which the cam is adapted to bear and actuate the same in one direction only, and connections between said lever and the presser-bar. 90

2. The combination of the presser-bar of a sewing-machine with a knee-lever and its cross-shaft, a flanged cam on the cross-shaft, and a lever acted on by the flanged cam, and connections between said lever and the presser-bar. 95

3. The combination of the presser-bar of a sewing-machine with a knee-lever and its cross-shaft, a cam on the cross-shaft, a spring-pressed lever acted on by said cam, and a stop and stop-lug to limit the movement of the lever, and connections between the latter and the presser-bar. 100

4. The combination of a knee-lever and its cross-shaft having a cam with brackets in 105

which the cross-shaft is mounted, a lever pivoted to a stud on one of the brackets and adapted to be acted upon by the cam, the lever and stud having on one side of the pivot a stop and stop-lug, and on the other side of the pivot projections, between which is a spiral spring.

5. The combination of the presser-bar of a sewing-machine with a lever and connections to the bar, a shaft having a cam to act on the said lever, and a knee-lever having a wedge-

shaped opening in its hub to fit over the end of shaft, and a set-screw to force the end of the shaft into the wedge.

In testimony whereof I have signed my name to this specification in the presence of two subscribing witnesses.

ALFRED L. MADISON.
